UNITED STATES PATENT OFFICE

MARTIN PAUL BLESER AND BERNARD PETER BLESER, OF CINCINNATI, OHIO

DESIGN FOR A BRACELET OR SIMILAR ARTICLE

Application filed August 20, 1929. Serial No. 32,468. Term of patent 7 years.

To all whom it may concern:

Be it known that we, MARTIN PAUL BLESER and BERNARD PETER BLESER, residing at Cincinnati, in the county of Hamilton and State of Ohio, have invented a new, original, and ornamental Design for a Bracelet or Similar Article, of which the following is a specification, reference being had to the accompanying drawing, forming part thereof.

We claim:

The ornamental design for a bracelet or similar article, as shown.

MARTIN PAUL BLESER.
BERNARD PETER BLESER.
